UNITED STATES PATENT OFFICE.

GABRIEL L. SAKAKEENY, OF ST. LOUIS, MISSOURI.

DESIGN FOR AN EDIBLE CONTAINER SHELL FOR ICE CREAM AND OTHER CONFECTIONS.

Application filed March 22, 1928. Serial No. 25,945. Term of patent 14 years.

To all whom it may concern:

Be it known that I, GABRIEL L. SAKAKEENY, a citizen of the United States, residing in the city of St. Louis and State of Missouri, have invented a new, original and ornamental Design for Edible Container Shell for Ice Cream and Other Confections, substantially as shown in the accompanying drawing, in which—

Fig. 1 is a plan view.

Fig. 2 is a side elevation.

Fig. 3 is an end elevation.

I claim:

The ornamental design for an edible container shell for ice cream and other confections.

GABRIEL L. SAKAKEENY.
